A. R. HOLLER

AUDIBLE SIGNAL AND FUEL CONTROL

Filed Feb. 20, 1923

Albert R. Holler Inventor.

By
Lancaster & Holler
Attorneys.

UNITED STATES PATENT OFFICE.

ALBERT R. HOLLER, OF ERIE, PENNSYLVANIA.

AUDIBLE SIGNAL AND FUEL CONTROL.

Application filed February 20, 1923. Serial No. 620,311.

To all whom it may concern:

Be it known that I, ALBERT R. HOLLER, a citizen of the United States, residing at Erie, in the county of Erie and State of Pennsylvania, have invented certain new and useful Improvements in Audible Signals and Fuel Controls, of which the following is a specification.

This invention relates to new and useful improvements in signaling devices and more particularly to a device of this character which is especially adapted for use in connection with the fuel supply for automobiles, launches, and other vehicles of this character.

The main object of the invention is the provision of a signal which will be automatically sounded to warn the operator of the vehicle that the fuel in the supply tank 20 has reached a predetermined level and that only enough fuel remains as a reserve supply for operating the vehicle a certain length of time or mileage distance before the fuel supply must be replenished.

Another object of this invention is the provision of a signal of the above character including means whereby the entire supply of fuel from the supply tank to the engine is cut off and locked, when not in use by 30 the owner to prevent the appropriation or use of the vehicle by unauthorized persons.

A further object of the invention is the provision of means whereby the reserve supply of fuel may be quickly and readily connected with the supply pipe leading to the engine after the signal has signified the exhaustion of the main supply, without the necessity of stopping the motor or of the operator leaving his seat.

A still further object of this invention is the provision of a signaling device, wherein the means for controlling the fuel supply from the main supply and the reserve supply is located in close proximity to the operator and readily accessible at all times.

With the above and other objects in view, the invention consists in the novel features of construction, the combination and arrangement of parts as pointed out in the appended claims and shown in the accompanying drawings.

Figure 1 is a diagrammatic view of a fuel supplying system used in connection with my improved signal.

Figure 2 is a top plan view of the means for controlling the signal.

Figure 3 is a vertical sectional view on the line 3—3 of Figure 4.

Figure 4 is a sectional view taken on the line 4—4 of Figure 3.

Referring now more in detail to the drawings in which various reference characters indicate the several parts throughout, it will be noted that there is included in the construction of applicant's device, as well as the operation, the main supply tank A generally of the type used on motor vehicles having suitable connection with the vacuum tank B arranged between the main supply tank A and the motor or engine, and arranged between the supply tank A and the vacuum tank B is my improved signaling device C.

In the specific arrangement of the several parts, the usual service line, which is indicated by the numeral 1 has one end thereof extending into the supply tank A to a point a short distance from the bottom as indicated in the diagrammatic view in Figure 1 and the other end thereof is connected with the signaling device C and passes therethrough into the pipe or tube 2 which leads to the vacuum tank B. In addition to the regular service line 1, I provide an additional pipe line 3, one end of which extends to the bottom wall of the tank A whereby the entire supply of fuel may be withdrawn from the tank. The additional pipe line 3 leads to the signaling device C, passes therethrough, and then through the pipe or tube which is connected with the tank B, whereby it will be noted that the entire supply of fuel contained within the tank A may be readily withdrawn therefrom.

My improved signaling device C comprises a valve casing 4 having the two inlet ports 5, 6, and the outlet port.

In order to provide for a suitable connection between the pipe lines 1 and 3 and the inlet ports 5 and 6, the L-shaped members 8 are provided, said L-shaped members having their inner ends extended into the ports 5 and 6 and the outer end suitably connected with the pipe lines 1 and 3 by means of the union nut 9.

Arranged within the valve casing 4 is a rotary valve 10 having an arcuate recess 11 formed therein, whereby upon rotative movement of the valve communication between a selected port opening 5 or 6 and the port opening 7 may be readily established,

as indicated by the dotted lines in Figure 4 or communication between the ports 5 and 6 and the port 7 may be entirely cut off as illustrated in full lines in Figure 4. The port 7 continues out through a neck portion 11' formed upon the exterior of the valve casing and opens into the interior of the signal member 12. This signal member 12 comprises the opposed arcuate portions 12' 10 which have their edges arranged in abutting relation and secured in any suitable manner. Outlet from the member 12 is established through the passageway 13 which is formed in the upright portion of the supporting arm 15 14, the supporting arm being provided with a nipple 15 through which the passage 13 extends and is connected with the pipe line 2 by means of the union nut 9', whereby it will be noted that communication may be 20 established between the tank A and tank B either through the port opening 5 or through the port opening 6.

The valve member 10 is contained within the casing 4 and held in proper relative position with respect to the several port openings in the casing by means of the coil spring 16 which is mounted upon the valve stem 17 and disposed between the closure plate 18 upon one side of the valve casing and the 30 washer 19 which is held in place upon the stem 17 by means of a suitable cotter pin 20. The valve member 10 is provided with an outwardly extending stop lug 21 which is adapted to engage the spaced shoulders 22 35 formed on the valve casing, whereby the limit of movement of the valve can be confined to the space between the shoulders 22, communication will be established between one of the ports 5 or 6 and the port 7, and 40 when moved in the opposite direction against the opposing shoulder, a similar communication between the other ports 5 or 6 and the port 7 may be established. Upon movement of the valve 10 so that the 45 stop lug 21 is disposed midway between the shoulders 22, the communication between the ports 5 and 6 and the port 7 is entirely cut off, the valve member being in the position illustrated in Figure 4.

50 The signaling device B is preferably supported upon a base plate 23 and attention is directed to the fact that this signaling device, particularly the controlling valve and the signal member itself, comprises two separate sections, connection of which is made by the soldering of the two parts of the member 12. The valve member and the signal member are connected to the base member 23 through the medium of the supporting arms 14 and 24, the outer ends of which are provided with winged portions 25, extending at right angles to the arms 14 and 24 and bolted or otherwise secured to the base plate as indicated at 26.

65 In order to actuate my improved valve

member whereby communication between the several ports in the valve may be established, any suitable form of cylinder lock may be used, the lock in the present instance being indicated by the numeral 27 and arranged in the dash board of the vehicle. The rotatable cylinder 28 of the lock 27 is provided at its inner end with an elongated opening, into which extends the elongated stem 29 formed in the valve member 10, 70 whereby it will be apparent that through the rotation of the cylinder 28 of the lock, the valve 10 will be readily actuated to selectively establish communication between the several ports of the valve casing. The base 80 plate 23 which supports the signaling device is connected with the dash board, which in the present instance is indicated by the numeral 31, by means of suitable securing bolts 32, and mounted upon the base plate 85 23 is the casing 33 which provides a housing for the signal device C. The casing 33 includes a substantially rectangular body portion of suitable type to entirely enclose the signal device and is provided on opposite 90 ends thereof with perforated ears 34 which are mounted upon the securing bolt 32 and retained in position by means of the detachable nut 35.

From the above, it will be readily apparent that when the supply tank A has a capacity supply of fuel therein or a sufficient amount of fuel whereby the inner end of the pipe line 1 will be immersed within the fuel and the valve member 10 arranged in position to connect the ports 5 and 7, direct communication will be established between the main supply tank A and the vacuum tank B through the pipe line 2, whereby the required amount of fuel will be supplied to the 100 vacuum tank. Attention is called to the fact that in the passage of the fuel from the main supply tank A to the vacuum tank B, it includes in its path of travel the signal member 12, the fuel passing through this signal member, through the passage 13, and into the pipe line 2. Should the supply of fuel within the tank A drop below the level of the inner end of the pipe 3, it will be noted that air will be sucked through the signal member 12 producing a whistling sound, the volume of sound depending on the proportions of the signal member, and the size of the passageway through the same, particularly the openings from the ports 7 and the 110 passageways 13.

It will be apparent from the above that through the audible sounding of the signal, the operator of the vehicle will be warned that his fuel supply has been reduced to a 125 limited amount, and that only a predetermined amount of fuel remains, whereby a predetermined distance may be travelled before the supply must be replenished. When the operator has been notified by the audible 130

sounding of the signal, that his main supply of fuel has become exhausted, he may readily establish communication between the pipe line 2 and the reserve pipe line by rotating the valve member 10 so as to bring the port openings 6 and 7 into communicating relation so that the reserve supply of fuel within the tank may then be utilized. The operator may readily actuate the valve 10 by inserting the key 36 into the cylinder 28 of the lock, said key being provided with suitable indentations to actuate the tumblers of the lock to permit rotation of the cylinder, whereby the valve member may be rotated to the desired position. When the valve member 10 is arranged in the position illustrated in Figure 4, the communication between the supply tank A and the vacuum tank B is entirely shut off so that none of the fuel within the tank A may be drawn upwardly into the tank B for use in operating the motor and in order to establish communication between the tank A and tank B it will be necessary for the owner or operator of the vehicle to insert the key 36 into the rotatable cylinder 28 so that the cylinder 28 may be readily rotated to impart movement to the valve and provide for connection between the ports 5 and 6 and the port 7. From the above it will be apparent that when the vehicle is not being used either by the owner or operator of the same, the valve member 10 may be rotated to the position shown in Figure 4, to cut off the supply of fuel to the engine and prevent the vehicle from being stolen or used by an unauthorized person.

The improved signal device D together with the means for controlling the same is attached to the dash board of the vehicle upon the outer face thereof and preferably arranged in such a position as to be disposed beneath the hood covering the motor and upon the side of the vehicle usually occupied by the operator, so that the device may be readily accessible by the operator at all times.

While I have shown and described the preferred form of my invention, it will be apparent that the various changes and alterations may be carried out without depart-

ing from the spirit of the invention or the scope of the appended claims.

I claim:

1. In a structure of the character described, a three way valve comprising a cylindrical casing having inlet ports formed in its periphery in spaced relation to each other circumferentially of the casing and an outlet port in its lower portion between the inlet ports, a valve block rotatably mounted in said casing and having a peripheral pocket for selectively connecting the outlet port with either of the inlet ports when the valve block is rotated, a tube leading from the outlet port, a convex disc carried by said tube, a mounting member, an arm extending from the upper portion of said valve casing and connected with said mounting member, a bracket element connected with the mounting member and having a tubular outer end portion adapted for connection with an outlet pipe, an upstanding tubular arm carried by said bracket element in spaced relation to its free end and communicating with the tubular outer end portion of the bracket member, and a disc carried by said upstanding arm and having its peripheral portion joined to the peripheral portion of the other disc, said discs having concave confronting faces. 80

2. In a structure of the character described, a three way valve comprising a cylindrical casing having inlet ports formed in its periphery in spaced apart relation to each other circumferentially of the casing and an outlet port in its lower portion between the inlet ports, a valve block rotatably mounted in said casing and having a peripheral pocket for selectively connecting the outlet port with either of the inlet ports when the valve block is rotated, a tube leading from the outlet port, a disc carried by said tube, a second disc having its peripheral portion joined to the peripheral portion of said first mentioned disc, said discs having concave confronting faces, and an outlet tube extending from the second mentioned disc. 95

ALBERT R. HOLLER.
